Primary Examiner—Bernard Ansher*Assistant Examiner*—Dominic Simone*Attorney, Agent, or Firm*—Ashen & Lippman[57] **CLAIM**

The ornamental design for a combined closure cap and straw, as shown and described.

DESCRIPTION

FIG. 1 is a perspective view of a combined closure cap and straw showing my new design;

FIG. 2 is a right side elevational view thereof;

FIG. 3 is a front elevational view thereof;

FIG. 4 is a top plan view thereof;

FIG. 5 is a bottom plan view thereof;

FIG. 6 is a left side elevational view thereof; and,

FIG. 7 is a rear elevational view thereof.

FIGS. 2-7 have been drawn on an enlarged scale relative to that shown in FIG. 1.
